EPPA H. RYON, OF WALTHAM, MASSACHUSETTS, ASSIGNOR TO CROMPTON & KNOWLES
LOOM WORKS, A CORPORATION OF MASSACHUSETTS.

WEFT-REFLENNISHING LOOM.

1,030,748.

Specification of Letters Patent. Patented June 25, 1912.

Application filed September 10, 1910. Serial No. 581,387.

To all whom it may concern:

Be it known that I, EPPA H. RYON, a citizen of the United States, residing at Waltham, in the county of Middlesex and State 5 of Massachusetts, have invented certain new and useful Improvements in Weft-Reflennishing Looms, of which the following is a specification.

My invention relates to automatic weft 10 replenishing looms of the type shown and described in U. S. Letters Patent, No. 933,492, and particularly to the bobbin selecting mechanism combined with the stationary magazine shown and described in U. S. 15 Letters Patent, No. 972,722, which mechanism is in this instance combined with a stationary magazine of a weft replenishing loom of the type shown and described in the Letters Patent, No. 933,492, above referred to, and also relates to combining the selecting mechanism with the shuttle box operating mechanism of the Crompton type, patented in U. S. Letters Patent, No. 600,488, so that said selecting mechanism will be 20 operated by said box operating mechanism. The bobbin selecting mechanism consists in this instance of four vertically moving bars, one for each compartment or 25 guide-way of the magazine. These bars are closely supported in guides, to have an up and down movement communicated thereto by operating fingers, above and below a 30 projection on the bar. The lower end of each bar has pivotally attached thereto one 35 arm of a rocking support or cradle, and the vertical movement of a bar communicates to 40 said support or cradle, a rocking movement, according to the vertical movement of said bars. The rocking of a cradle causes the 45 selection of a bobbin from the magazine, to be transferred in the usual way.

The object of my invention is to improve upon and simplify the construction of the bobbin selecting mechanism above referred 45 to. Instead of having two sets of fingers, which operate the vertically moving bars up and down, in order to operate the cradles to drop a bobbin from its compartment to the discharging end of the magazine, I use 50 in this instance one lever only, which is operated by a single cam, and which, on the indication of the substantial exhaustion of filling on a bobbin, first moves the vertically extending bar upwardly, to rock a 55 cradle and allow the lowest bobbin in a

compartment to move down the distance of one bobbin and be held there, and then, when the corresponding shuttle returns to the magazine end, moves the bar down again to rock the cradle and allow the bobbin to drop down to the lower discharging end of the magazine, preparatory to being transferred into the shuttle, as usual.

The further object of my invention is to combine the bobbin selecting mechanism 60 with the shuttle box operating mechanism of the Crompton type above referred to, through intermediate connections, so that said selecting mechanism will be operated by the operation of said box operating 65 mechanism.

I have only shown in the drawings detached portions of a weft replenishing loom of the class above referred to, with my improvements applied thereto, sufficient to enable those skilled in the art to understand 70 the construction and operation thereof.

Referring to the drawings:—Figure 1 is an end view of a loom of the class referred to, showing a part of the inner end of a 80 stationary magazine, and parts of the selecting mechanism, and intermediate connections to the compound levers of the shuttle box operating mechanism of the Crompton type referred to, and also the lay and 85 movable shuttle boxes; the shuttle boxes are shown partially in section. Fig. 2 is an inner end view of the magazine, and the bobbin holding and selecting mechanism of my improved construction. Fig. 3 is a 90 front view of some of the parts shown in Fig. 2, looking in the direction of arrow *a*, same figure. Fig. 4 is a section, on line 4-4, Fig. 2, looking in the direction of arrow *b*, same figure. Fig. 5 is an inner end view of 95 a detached portion of the magazine, and the transferring mechanism, looking in the direction of arrow *c*, Fig. 3. Fig. 6 shows an enlarged scale of the compound levers shown in Fig. 1, detached. Fig. 7 shows a 100 plan view of the compound levers shown in Fig. 6, looking in the direction of arrow *d*, same figure. Fig. 8 shows some of the parts in Fig. 3, in a different position. Fig. 9 corresponds to Fig. 8, but shows some of 105 the parts in a different position, and, Fig. 10 corresponds to Fig. 9, but shows some of the parts in a different position.

In the accompanying drawings, 1 is the loom side, 2 is the breast beam, 3, (Fig. 5), 110

the lay beam, having a stationary shuttle box 4 on one end for a shuttle 5. On the end of the breast beam 2 is secured a stationary stand 6, which has rigidly connected therewith the inner end 7 of the magazine, which in this instance has four vertically extending compartments or guide-ways 7', for the heads of the bobbins, (not shown), which drop down by gravity to the lower discharging end 7" of the magazine. Each compartment or guide-way 7' is provided at its lower end with mechanism for supporting a set of bobbins therein, preparatory to their passage to the discharging end 7" of the magazine to be transferred into the shuttle.

The holding and releasing mechanism consists of a rocking support or cradle 8, pivotally mounted at the lower part of the magazine. The transerrer arm 9, (Fig. 5), has a downward extension 9' thereon which carries a dagger 10, which is adapted to be moved into the path of and be engaged by the bunter 11 on the lay beam 3, in the usual way.

On the loom side 1, and extending out therefrom is a stand 12, (Fig. 3), which forms a support for the feeler guide 13 of the filling feeler or detector, which in this instance may be of the type shown and described in the Letters Patent, No. 972,722, above referred to, and is not particularly shown in the drawings. The feeler or detector is adapted to operate the upright lever 14, which has its hub 14' secured on the shaft 15, which is loosely mounted in bearings 12' and 12", on the stand 12. A helically coiled torsion spring 16 encircles said shaft 15, to yieldingly hold the lever 14 toward the feeler guide 13; the other end of the shaft 15 has secured thereon the hub 17' of an upright lever 17. The end of said lever 17 is pivotally connected to a horizontally extending rod or plunger 18, (Figs. 2 and 5), guided at 12'" on the stand 12, and forms a holding point, or fulcrum, for the end of a horizontally extending lever 19, (Fig. 3), which has one end extending into the upright slotted portion 12'" on the stand 12.

A rocking motion is communicated to the lever 19 by a cam and lever on the loom, not shown, through connector 20, which is provided with a rod head 21, and is vertically guided in a boss 12' on the stand 12. The upper yoke-shaped end 21' on the rod head 21 has pivotally connected thereto the hub of the lever 19, to rock said lever, and on the substantial exhaustion of filling in the running shuttle, through the indication of the filling detector, to operate a cradle to drop a bobbin to the discharging end of the magazine, as shown and described in Letters Patent, No. 933,492, above referred to.

The upright vertically moving members or bars 22, which in this instance form a

part of my improvements, are provided with weighted hooks 23 at their upper ends, which hooks are adapted, on the downward movement of a bar 22, to engage and rock a lever 24, (Fig. 10), which has its hub 24' secured to the rock shaft 25. The vertically moving members or bars 22 have in this instance two notches 22a, on one edge thereof, see Fig. 8, and a spring actuated plunger 22b is adapted to enter either one of the notches, and to act as yielding means to retain a member or bar 22 in its raised or lowered position, as fully shown and described in Patent, No. 933,492, above referred to.

The rock shaft 25 has secured thereon the hub 26' of an arm 26, (Fig. 3). A stud 27 enters a hole in a block 28, which is adapted to loosely slide in an elongated opening 29' in a lever 29, which has its hub 29" loosely mounted on a stud 30. A helically coiled expansion spring 31 bears at one end against the block 28, and at its other end against the hub 29" of the lever 29, and acts to hold and lock the lever 26, and lever 29 in their upper and lower position. Extending out from the hub 29" on the lever 29 is a second arm 32, the outer end of which is pivotally connected to a downwardly extending connecting rod 33; the lower end of the connecting rod 33 is provided with a vertically extending plate 34, (Fig. 5), which is adjustably secured on the rod 33. The plate 34 has an elongated opening 34', into which extends a stud 34a on the stand 12, which is adapted to hold and guide the plate 34 in a vertical plane. A projection 34" extends from the plate 34 and below the dagger 10, which when the plate 34 is raised, causes the dagger 10 on the transerrer arm 30 to be raised into the path of the bunter 11 on the lay beam 3, to be engaged by the bunter to operate the transerrer arm 9, to transfer a bobbin into a shuttle 5, in the usual way.

The bearings 7'" on the magazine have loosely mounted therein the longitudinally moving rod 36; one end of said rod 36 has a collar 37 secured thereon, which has an annular groove 37', into which extends a side extension 38' on one arm of an angle lever 38, which has its hub 38" loosely mounted on a stud 39 carried on a stand 40; the other arm of the angle lever 38 is adjustably connected, through a slot and bolt connection, with the upper end of a wire 41, (Figs. 1 and 2). The lower end of the wire 41 is connected to one end of a flexible connection or chain 48; said chain 48 passes over a guide sheave 49, and over a second guide sheave 50, (see Fig. 1), mounted on a stand 51 on the left hand loom side, and is attached to a lever of the compound lever mechanism, to be hereinafter described.

The compound levers are operated through the well known shuttle box operat-

ing mechanism of the Crompton type, shown and described in U. S. Letters Patent, No. 600,488, above referred to. The box motion consists of two mutilated pinions 52, fast on shafts 53, and having movable teeth, which are operated through the pattern indicating surface or chain, not shown, and moved into and out of operative connection with a master gear 54, fast 10 on the bottom shaft 55. The opposite ends of the shafts 53, which are carried on a stand 56, are connected, through crank connectors 57 and 58, with the box operating lever 59, which, through a link or connector 60, is connected with the vertically moving rod 61, which supports on its upper end the shuttle boxes 62; in this instance four in number, carrying the shuttles 5. Each shuttle 5 preferably has 20 a bobbin or filling carrier therein of a different color. The lay 3, which is carried on the lay swords 63, pivotally mounted at their lower ends, is operated, through the crank connector 64, by the crank shaft 65, 25 in the usual way.

All of the above mentioned parts may be of the usual and well known construction, and particularly described in Letters Patent, No. 933,492, and No. 600,488, above 30 referred to.

I will now describe my improvements. One end of the horizontally extending lever 19 see Figs. 8, 9, and 10 extends, as above stated, within the slotted part 12", and 35 is adapted to bear on its upward movement, in this instance with its upper edge, against a pin 12^b, and on its downward movement the lower edge rests upon the rod or plunger 18, in case said rod or plunger is left 40 in the path of the movement of the lever 19, on the substantial exhaustion of filling on the bobbin in the active shuttle. The other end of the lever 19 has pivotally connected thereto a rod head 42' on the upwardly extending rod or connector 42. The upper end of the connector 42 is pivotally connected to a pin 43 on a lever 44, which has its hub 44' loosely mounted on the rod 36, (Fig. 4), and is prevented from having 45 longitudinal movement on said rod by the two bosses 7". The lever 44 is provided in this instance with lugs 44", adapted to loosely receive the spring actuated bolt 45, which, through the action of a helically 50 coiled expansion spring 46, when the lever 44 is in a horizontal position, bears against the stand 6 see Fig. 3 to prevent the lever 44 moving downwardly, through the action of the lever 19. The rod 36 has secured 55 thereon and longitudinally moving therewith, the hubs 47' on the operating fingers 47 see Fig. 4. A side extension 47" on the hub 47', extends loosely into a notch or recess in the lever 44. The up and down 60 movement of the lever 44 will communi-

cate, through the extension 47", an up and down movement to the fingers 47.

On the inside of the end plate of the magazine 7, and loosely guided thereon, are the four vertically moving bars 22 above 70 referred to, one for each compartment. The lower end of each bar 22 has in this instance the enlarged portion 22', provided with a slot or opening 22", having an offset therein, see Fig. 2, to loosely receive the 75 end of a pin 8', which is secured at its other end to an arm of the rocking support or cradle 8. The offset opening 22" acts to rock a cradle 8, and to lock and hold the same in its two positions, on the up and down movement of a bar 22, and also allows of a continued movement of the bars 22, to operate a connection to the fingers 47, after the cradle 8 has been moved a sufficient amount to drop a bobbin out of said 80 cradle. Each bar 22 has in this instance two projections 22'" thereon, which are adapted to extend in the path of the fingers 47 to be operated thereby.

The upward movement of any one of the 90 sliding bars 22, will cause the cradle 8 connected therewith to have partial rotation, allowing a bobbin to drop into the cradle, and on the downward movement of the bar 22, through the partial rotation of the cradle 95 8, the bobbin will be released and dropped to the lower discharging end of the magazine. At the same time, on the further downward movement of the bar 22, the weighted hook 100 23 at its upper end, operates the lever 24, and through the intermediate connections above described, raises the dagger 10 into the path of the bunter 11, in order to transfer a bobbin into the shuttle.

I will now describe the mechanism for controlling the longitudinal movement of the rod 36 of the bobbin selecting mechanism. The chain 48, above mentioned, is connected to one arm of a lever 66, see Fig. 6; said lever 66 is pivotally mounted on a stud 67 on an arm 68' on the bearing 68 of the bottom shaft 55. The opposite end of the lever 66 carries a stud 69, on which is loosely mounted the hub 70' of a balancing lever 70, comprising two arms which have the engaging ends 70" and 70'", said engaging ends in this instance, are adapted to ride upon the periphery of two cams 71 and 72, respectively, which have their hubs 71' and 72' secured on the shafts 53 of the mutilated pinions 52. The revolving of the mutilated pinions 52, to operate the box motion lever 59, will, through cams 71 and 72, operate the balancing lever 70, and the lever 66, and communicate, through the chain 48, and angle lever 38, a longitudinal movement to the rod 36 in one direction, to cause it to be moved, according to the movement of the shuttle boxes, for the selection of the bobbins from the magazine. A helically coiled 115 120 125 130

tension spring 38^a, see Figs. 1 and 2, attached to the lever 38 and to a stationary hook 38^b, serves to move said lever and rod 36 in the opposite direction.

6 From the above description in connection with the drawings, the operation of my improvements will be readily understood by those skilled in the art, and briefly is as follows:—When a bobbin has a sufficient supply of filling thereon, the filling detector, which in this instance may be of the type shown and described in Letters Patent, No. 972,722, above referred to, will engage at its inner end the filling in the shuttle, as the lay 10 beats up, and be moved backwardly to move the lever 17, so that the rod or plunger 18 is moved out of the path of movement of the free end of the lever 19, to allow said end to 15 freely move downwardly to the position shown in Fig. 8, thus leaving the lever 44 and finger 47 at rest, in their horizontal or center position, as shown in Fig. 8.

In case the filling on the bobbin in the active shuttle is practically or substantially 20 exhausted, then as the lay beats up, the filling 25 feeler does not operate the lever 17, and the rod or plunger 18 is in the path of movement of the free end of the lever 19, as shown in Fig. 9, thus forming a fulcrum 30 for said free end, and allowing the opposite end of the lever 19 to be moved downwardly, to operate the lever 44, and the finger 47 to move upwardly a vertically 35 moving bar 22, to allow a bobbin to drop into a cradle 8. On the next upward movement of the lever 19, its free end bears 40 against the pin 12^b, and causes the opposite end of the lever 19 to move upwardly, see Fig. 10, to operate the lever 44 and finger 47, and on the same position of the drop shuttle 45 boxes, to move downwardly the vertically moving bar 22, to drop a bobbin to the discharging end 7" of the magazine, and at the same time raise the dagger 10, as above 50 stated, into the path of the bunter 11, to transfer a bobbin into the active shuttle.

It will be understood that the details of construction of my improvements may be varied if desired.

50 Having thus described my invention, what I claim as new and desire to secure by Letters Patent is:—

1. In a weft replenishing loom, a lay, 55 shifting shuttle boxes, means to operate the same, a magazine having two or more compartments for spare weft carriers a support for the weft carriers in each compartment, a device adapted to rock about a pivotal center, and to coöperate with said supports, and 60 connections intermediate said device and said supports, means to shift said device into operative position for the different supports, according to indications of patern surfaces, and means to operate said device to impart a 65 movement to said supports in one direction,

to start a weft carrier toward a position to be transferred, and means to operate said device to impart a movement to said supports in the opposite direction to allow said weft carrier to complete its movement 70 to a position to be transferred into the active shuttle.

2. In a weft replenishing loom of the class described, a magazine having two or more compartments for weft carriers, a movable support for said carriers in each compartment shifting shuttle boxes, a shifting shuttle box operating mechanism, a device adapted to rock about a pivotal center to cause the movement of said supports in a 80 forward and backward direction, and connections intermediate said device and said supports, means connected with said shifting shuttle box operating mechanism, to move said device in unison with said shifting 85 shuttle boxes, and means to cause the co-operation of said device with said supports.

3. In a weft replenishing loom of the class described, a lay, shifting shuttle boxes, mechanism for operating the same, a magazine having two or more compartments for 90 weft carriers, supports for said weft carriers, a device to operate said supports, and connections intermediate said device and said supports, cams arranged on said shifting shuttle box mechanism, and connections from said cams to said device to move said device longitudinally.

4. In a weft replenishing loom of the class described, a magazine having two or 100 more compartments for weft carriers, supports for the weft carriers, movable slides connected with said supports, a device adapted to rock about a pivotal center, and means for operating the same to positively 105 move said slides and said carriers in a forward and backward direction.

5. In a magazine of a weft replenishing loom, having two or more compartments for 110 spare weft carriers, supports for said carriers, movable slides operatively connected to said supports, a device to coöperate with said slides, and means to impart a longitudinal motion to said device, and means to rock said device about a pivotal center, to 115 move said slides positively in two directions.

6. In a weft replenishing loom of the class described, a magazine having two or more compartments for spare weft carriers, supports for said weft carriers, members operatively connected to said supports, a device adapted to rock about a pivotal center under the control of a feeler mechanism, to operate a predetermined member in one direction, on the practical exhaustion of the filling in an active shuttle, and means connected with said device to operate said member through said device in the opposite direction, when the same shuttle is again returned to the magazine end of the loom.

7. In a magazine of a weft replenishing loom, having two or more compartments for spare weft carriers, supports for said carriers, members operatively connected to said supports, yielding means to retain said members in either of two positions, a device adapted to rock about a pivotal center to coöperate with said members, to move the same from one position to another, means to shift said device to coöperate with a predetermined member, and means to cause the coöperation of said device with said members.

8. In a magazine of a weft replenishing loom having two or more compartments for spare weft carriers, supports for said carriers, members operatively connected to said supports, a movable device to coöperate with said members, a movable member pivotally connected, adjacent its center, to a reciprocating slide, and said slide, and means to operate said slide to move said pivotal member, a connection from one end of said pivotal member to said movable device, a feeler controlled rod or plunger adapted to coöperate with one side of the free end of said pivotal member when the filling is substantially exhausted in the active shuttle, to cause a movement of any of the first mentioned members in one direction, when engaged by said movable device, and a stop to be engaged by the other side of the free end of said pivotal member to cause a movement of any of the first mentioned members in an opposite direction, when engaged by said movable device.

9. In a magazine of a weft replenishing

loom, having two or more compartments for spare weft carriers, supports for said carriers, members connected to said supports, a device to coöperate with said members, and means to impart a longitudinal motion to said device, and means to rock said device about a pivotal center in one direction, and also in an opposite direction, and means to hold said device in its intermediate position.

10. In a magazine of a weft replenishing loom, having two or more compartments for spare weft carriers, supports for said carriers, members connected to said supports, a device to coöperate with said members, and means to impart a longitudinal motion to said device, and means to rock said device about a pivotal center in one direction, and also in an opposite direction, and means to yieldingly hold said device in its intermediate position.

11. In a magazine of a weft replenishing loom, having two or more compartments for spare weft carriers, supports for said carriers, members connected to said supports, a device to coöperate with said members, and means to impart a longitudinal motion to said device, and means to rock said device about a pivotal center in one direction, and also in an opposite direction, and means to yieldingly hold said device in its intermediate position during its longitudinal motion.

EPPA H. RYON.
